MES PATERSON, OF ELIZABETH, NEW JERSEY, ASSIGNOR TO THOMAS POTTER SON AND CO., OF PHILADELPHIA, PENNSYLVANIA.

Design No. 4,416, dated October 11, 1870.

DESIGN FOR AN OIL-CLOTH PATTERN.

The Schedule referred to in these Letters Patent and making part of the same

I, JAMES PATERSON, of Elizabeth, county of Union, state of New Jersey, have invented or produced a Design for an Oil-cloth Pattern, of which the following is specification.

The figure in the accompanying drawing illustrates, partly in outline, and partly filled in with the ornaments, my design for an oil-cloth pattern, the main characteristic of which consists of a series of bordered tablets, A, shaped and arranged in respect to each other so a series of tablets, B, and square figures D, in the manner clearly illustrated in the drawing.

The borders of the tablets A consist of a series of stripes, x, and in each of these tablets is a scroll ornament, y.

The ornamentation of the tablets B and square figures D is too clearly shown in the drawing to need explanation.

I claim—

1. An oil-cloth pattern, composed of the tablets A and B and figures D, formed and arranged in respect to each other in the manner illustrated in outline in the accompanying drawing, irrespective of their internal ornaments.

2. The tablets A, bordered and ornamented as shown and described.

3. The tablets B, bordered and ornamented as shown and described.

In testimony whereof, I have signed my name to this specification in the presence of two subscribing witnesses.

JAS. PATERSON.
